US0D1017882S

(12) **United States Design Patent** (10) Patent No.: **US D1,017,882 S**
(45) Date of Patent: ** Mar. 12, 2024

(54) **LED LIGHT**

(71) Applicant: **JIAXING SUPER LIGHTING ELECTRIC APPLIANCE CO., LTD,**
Zhejiang (CN)

(72) Inventors: **Tao Jiang**, Zhejiang (CN); **Ming-Bin Wang**, Zhejiang (CN); **Chen-Kun Chen**, Zhejiang (CN); **Dong-Mei Zhang**, Zhejiang (CN)

(73) Assignee: **JIAXING SUPER LIGHTING ELECTRIC APPLIANCE CO., LTD,**
Zhejiang (CN)

(**) Term: **15 Years**

(21) Appl. No.: **29/885,156**

(22) Filed: **Feb. 21, 2023**

Related U.S. Application Data

(62) Division of application No. 29/769,547, filed on Feb. 5, 2021, now Pat. No. Des. 995,868.

(57) **CLAIM**

The ornamental design for an LED light, as shown and described.

DESCRIPTION

FIG. 1 is a perspective view of an LED light showing our new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top elevational view of FIG. 1; and,

FIG. 7 is a bottom elevational view of FIG. 1.

The broken lines illustrate portions of the LED light that form no part of the claimed design.

1 Claim, 4 Drawing Sheets
